UNITED STATES PATENT OFFICE.

EDWARD A. MASON AND HEDLEY VICARS HAYES, OF ST. JOHN, NEW BRUNSWICK,
CANADA.

DISPLAY AND DISPENSING CABINET.

1,258,801.

Specification of Letters Patent. Patented Mar. 12, 1918.

Application filed July 5, 1917. Serial No. 178,693.

To all whom it may concern:

Be it known that we, EDWARD ARMSTRONG MASON and HEDLEY VICARS HAYES, subjects of the King of Great Britain, and residents 5 of St. John, in the Province of New Brunswick and Dominion of Canada, have invented a certain new and useful Improvement in Display and Dispensing Cabinets, of which the following is a specification.

- 10 The present invention relates to dispensing cabinets, and more particularly to a cabinet adapted to display goods to be vended. An object of the present invention is to provide a cabinet with an annular space to 15 retain a relatively small quantity of goods in position over a relatively large surface area to provide a relatively large display, and to so hold the displayed goods that they will not be decreased in quantity by withdrawal of the main bulk of the goods in the 20 cabinet.

The invention further aims at the provision of a sanitary cabinet which will house and protect from dust, in such, and handling 25 by the customers, goods to be vended, and also the goods placed on display.

- 30 A further object is to provide a cabinet comprising relatively few parts peculiarly and detachably interfitted and admitting of the easy separation of the parts for cleaning and ventilating the interior of the cabinet; to provide a cabinet which will seal the goods of delicate flavor from absorbing foreign flavors from surrounding goods; which 35 is simple and economical in construction and manufacture, and comprises relatively few parts which may be readily removed and replaced when broken; to provide a cabinet having a base portion of such form that the 40 latter may be assembled in a closely spaced apart row of cabinets of similar construction; and to provide a cabinet with a bin in the lower portion thereof into which the goods to be vended are fed by gravity, 45 and to provide means in the bin for providing a space into which may be returned excess quantities of goods withdrawn from the bin.

The above, and various other objects and 50 advantages of this invention will be in part described, and in part understood, from the following detailed description of the present preferred embodiment, the same being

illustrated in the accompanying drawing wherein:

55 Figure 1 is a side elevation of a combined display and dispensing cabinet constructed according to the present invention.

Fig. 2 is a vertical section taken substantially centrally through the same.

60 Fig. 3 is a horizontal section taken on a plane indicated by the line 3—3 in Fig. 1, and looking downwardly toward the base of the cabinet.

65 Referring to this drawing, 10 designates a base which may be in the form of a casting, and which is hollow. The base 10 is provided with downwardly flaring front and side walls, and is provided about its lower open end with an outstanding attaching 70 flange 11 provided with suitable apertures 12 adapted to receive fastening devices for holding the base 10 to a counter, a shelf or the like. The base 10 is provided with a flat top and with a relatively large circular opening formed centrally of the top.

75 Within the base 10 is fitted a bin 13, the latter being in the form of a substantially rectangular receptacle substantially filling the base 10 and provided at its rear side 80 with a relatively broad projecting mouth 14 formed by a continuation of the bottom of the bin 13 and inclining the continuation thereof upwardly into a plane which is horizontal and which is located below the top of 85 the bin. The mouth 14 is provided with a hinged closure or cover 15 which rests upon the upper edges of the mouth 14, and which is pivoted at its outer edge portion to the mouth 14 by the hinge 16. The opening of 90 the mouth 14 is continued upwardly in the rear wall of the bin 13, as shown to advantage in Fig. 2, and the cover 15 is provided with an upstanding flange 17 which engages across the rear wall of the bin 13 and closes 95 the opening therethrough. A finger loop 18 is secured to the cover 15 in the angled portion thereof between the body of the cover 15 and the upstanding flange 17. The finger loop 18 is arranged preferably intermediate the lateral edges of the cover 15 100 and in position to be readily grasped by the fingers for raising and swinging the cover 15 about its hinge 16 and into open position for the introduction of a tube or the like 105 into the mouth portion.

The bin 13 is of a height which extends from the plane of the attaching flange 11 upwardly into a horizontal plane spaced slightly below the horizontal plane of the 5 top of the base 10. The mouth 14 of the bin 13 projects rearwardly through a relatively large opening or slot formed in the rear wall of the base 10.

The top 19 of the bin 13 is provided with 10 a circular opening of less diameter than the opening in the top of the base 10 which is adapted to be arranged concentric thereto when the bin 13 is located in the base. An opaque cylinder or container 20, preferably 15 of metal, is open at opposite ends and is adapted to seat at its lower end upon the top 19 of the bin at the inner marginal edge portion thereof, the interior diameter of the container 20 being substantially equal to the 20 diameter of the opening through the top 19. The top 19 is provided on its under side, and about the openings therethrough, with a depending feeding flange 21 which has at its 25 upper edge portion an outturned attaching portion adapted to be riveted, screwed or otherwise secured to the top 19 and against the underside thereof. The feeding flange 21 is of any desired length and is adapted to direct the contents of the receptacle 20 into 30 a substantially pyramidal pile and prevents the spilling of the mouth 14. When a quantity of the contents have been removed from the bin 13 through the mouth 14, the flange 21 directs a corresponding quantity of the 35 goods from the container 20 into the bin, and should it be desired to return an excess quantity of the goods removed, it is only necessary to replace the same in the forward end of the mouth 14 and above the pyramidal pile of the goods.

A transparent cylinder or casing 23 of greater diameter than the container 20 projects downwardly through the opening in the top of the base 10 and is seated upon the 45 upper wall 19 of the bin 13. A plurality of spacers 24, in the form of angle irons, are riveted or otherwise suitably secured to the exterior surface of the container 20 and project radially therefrom a distance equal to 50 the width of the annular space formed between the cylinders 20 and 23. The spacers 24 hold the cylinders in substantially true concentric relation. The outer transparent cylinder 23 is held to the base 10 by the provision of a clamping strap 25, the major portion 55 of which extends downwardly through the opening in the base 10 and is provided therewith an outstanding substantially annular retaining flange 26 adapted to engage against the under side of the top of the base 10 and hold the strap 25 from upward movement through the opening in the base. The strap 25 is curved substantially circular, and is provided on its closely spaced-apart 60 ends with outturned ears 27 arranged above

the top of the base 10 and which are connected together by a clamping bolt 28 adapted to be tightened for contracting the strap 25 about the outer cylinder 23 for detachably holding the latter to the base 10 and 70 upon the top of the bin 13.

The spacers 24 are preferably arranged upon the upper and lower portions of the container 20 to space the top and bottom thereof equi-distantly from all sides of the 75 outer transparent shelf or casing 23. The inner and outer cylinders 20 and 23 are substantially of equal height, and a cover 29 is fitted over the upper open ends of the cylinders and provided with a suitable knob or 80 handle 30 by means of which the cover may be easily removed. The under side of the cover 29 is recessed and rabbeted to fit closely upon the upper edge of the transparent cylinder 23 to seal the upper end of 85 the cabinet.

The base flange 11 has the openings 12 thereof formed in the opposite side portions of the flange 11 so that a plurality of the 90 cabinets may be arranged in a row in closely spaced-apart relation with the flanges 11 thereof overlapping at the adjacent sides of the cabinet and secured together by a common fastening device.

The parts of the cabinets may be separated 95 without removing the base 10 from the counter or shelf by merely loosening the strap 25 and lifting the cylinders 20 and 23 from the bin 13. The bin 13 may now be slid rearwardly through the opening in the rear 100 wall of the base 10, and the parts may thus be readily cleansed and ventilated.

In use, when the parts are in position as shown in the drawing, a relatively small quantity of the goods may be placed in the annular compartment between the cylinders 105 20 and 23, and the compartments may be filled to the top with the goods so as to display a relatively large quantity or surface area of the goods. The main bulk of the goods is placed in the inner cylinder 20, and is not exposed to view. The goods are dispensed from the inner opaque cylinder 20, and the removal of the main bulk of the 110 goods does not disturb the quantity of the goods arranged in the display compartments or annular space.

It is of course understood that various changes may be made in the construction and design of the above specifically described parts of the invention without departing from the spirit thereof, and being restricted only by the scope of the following claims.

We claim:—

1. In a combined display and dispensing cabinet, the combination of a base, a cylinder rising from the base and adapted to receive a quantity of goods, a bin arranged in the base communicating with the lower 130

end of said cylinder and adapted to receive the goods therefrom, and an outer transparent cylinder rising from the base about said first cylinder and providing therebetween an annular space adapted to receive a relatively small quantity of the goods to display the same at all sides of the cabinet.

2. In a cabinet, the combination of a hollow base, a bin detachably fitting in the base and provided with a mouth portion extending rearwardly therethrough, a pair of concentric cylinders rising from the base and providing therebetween an annular display compartment, the top of said bin comprising a closure for the lower end of said compartment, said bin having an opening in its top wall communicating with the inner compartment, feeding means arranged about the openings in the bin for distributing goods from the inner compartment into the bin, and means carried by the base for holding the cylinders in position.

3. In a cabinet, the combination of a hollow base provided with an opening in its top, a bin detachably arranged within the base and having a smaller opening in its top, a pair of concentric cylinders arranged in spaced relation upon the top of the bin with the inner cylinder communicating with the opening in the bin and the space between the cylinders closed by the top of the bin, and clamping means carried by the base for engagement with the outer cylinder to hold the same to the base.

4. In a cabinet, the combination of a hollow base, a bin detachably mounted in the base and provided with a mouth portion extending through the rear side of the base, a hinged closure for closing said mouth of the bin, a pair of concentric cylinders bearing at their lower ends upon the upper wall of the bin and providing an annular passage therebetween closed at its lower end by the wall of the bin, spacers arranged between the cylinders for maintaining the same in

concentric relation, and a clamping element carried by the base and engaging the outer cylinder to bind the same in position.

5. In a cabinet, the combination of a hollow base, a bin arranged within the base and having an opening in its top, said base having an opening in its top of greater diameter than the opening in the bin, a pair of concentrically arranged cylinders projecting downwardly through the opening in the base and resting upon the upper wall of said bin about the opening therein, spacers arranged between the cylinders, a clamping element carried by the base and engaging the outer cylinder to hold the cylinders in position, and a feeding flange depending from the top of the bin into the latter and about the marginal edge of the opening through the bin.

6. In a cabinet, the combination of a hollow base, a bin detachably mounted in the base and adapted to slide into and out of position through the rear wall of the base, said bin having an upwardly opening mouth projecting from the rear side thereof and through the rear wall of the base, a hinged cover mounted on the mouth of the bin adapted to normally close the mouth, a feeding flange depending from the top of the bin and the latter having an opening within the flange through the top of the bin, a pair of concentric cylinders mounted on the top of the bin and projecting upwardly through the base, the top wall of the bin forming a closure for the lower end of the annular compartment between the cylinders, spacers arranged between the cylinders, a clamping element carried by the base engaging the outer cylinder to hold the latter in position, and a cover detachably mounted upon the upper ends of the cylinders to close the annular compartment and to close the inner cylinder.
